[57] **CLAIM**

The ornamental design for an actuator handle for a beverage dispensing valve, substantially as shown and described.

DESCRIPTION

FIG. 1 is a front elevational view of an actuator handle for a beverage dispensing valve, showing our new design, the back elevational view being identical to the front elevational view;

FIG. 2 is a side elevational view thereof, both sides being identical;

FIG. 3 is a top plan view thereof;

FIG. 4 is a bottom plan view thereof;

FIG. 5 is a sectional view through V—V of FIG. 1.

FIG. 2

FIG. 1

FIG. 3

FIG. 4
